W. DALTON

RAILROAD TRACK STRUCTURE

Original Filed Feb. 1, 1927

Fig.1.

Fig.2.

Inventor:
William Dalton,
by Alfred V. Bobst.
His Attorney.

UNITED STATES PATENT OFFICE.

WILLIAM DALTON, OF GLENVILLE, NEW YORK.

RAILROAD-TRACK STRUCTURE.

Original application filed February 1, 1927, Serial No. 165,136. Patent No. 1,657,242, dated January 24, 1928. Divided and this application filed September 20, 1927. Serial No. 220,811.

This application is a division of my application Serial Number 165,136, filed February 1, 1927, now Patent 1,657,242, January 24, 1928.

5 The invention relates to railroad track structures and especially to railroad track structures wherein the ties are formed from metal.

10 The object of the invention is to provide an improved form and construction of anti-creeping arrangement for both the rails and the ties, and for a consideration of what I believe to be novel and my invention, attention is directed to the following specification and the claims appended thereto.

15 In the drawing, Fig. 1 is a top plan view of a track structure embodying my invention, and Fig. 2 is a perspective view thereof.

Referring to the drawing, 1 indicates 20 track ties which are formed of metal and which embody as a part of their structure angle bars 3 and 4 located at opposite ends of the tie. In the present instance each tie is shown as comprising two lengths of tie bars 5 and 6 which are fastened together at their ends by the angle bars 3 and 4 and on their top surfaces by plates 7 and 8 which form supports for the track rails. The plates 7 and 8 are shown as being standard 25 tie plates and they are welded in place as is illustrated at 9. The rail positioning and holding rib of the tie plates is indicated at 10. In the tie plates are two spaced openings 11 and 12 between which the base flange of 30 the track rail lies. The head of the track rail is indicated at 13, the web is indicated at 14 and the base flange is indicated at 15. The rail is fastened to the ties by fastening 35 means comprising two members, a rail clamping member 16 and a fastener 17. The rail clamping member comprises a short U-shaped bar having a central portion 18 which lies in the tie plate opening, an upper inturned end 19 which projects over the base flange of the rail and a lower inturned end 20 which extends beneath the tie plate. It is held in place by the fastener 17 which is in 40 the form of a spring key, as shown.

The track tie structure and the rail-fastening means as so far described form no part 45 of my present invention, the track tie structure forming the subject matter of my Patent 1,657,241, January 24, 1928, and the fastening means forming the subject matter of 50 my Patent 1,657,242, already referred to.

They are illustrated only by way of example and are to be taken as typical of any suitable construction to which my invention may be applied.

According to my invention, I make the angle bars 3 and 4 at the ends of the ties of a length such that they abut against each other as is indicated at 21, and I then provide at suitable points on the rail base flanges projections 22 which stand on opposite sides of the end 19 of a rail fastener. Projections 22 may be built up by fusing metal to the rail flange, using a welding machine for the purpose, or they may be formed on the rail when it is rolled. Projections 22 need be 60 provided only at spaced points, it being unnecessary to provide them at every tie. In fact, at one tie within the length of each rail may be sufficient. With this arrangement, creeping of the rail is prevented by projections 22 engaging ends 19 of the rail fasteners. And the abutting angle bars at the ends of the ties serve to distribute the stress among the several ties so that the stress is not borne by the single tie appurtenant to 65 the projections 22. Since the angle bars at the ends of the successive ties abut one another, each individual tie is held from displacement by the adjacent ties.

By the above-described arrangement, 70 therefore, wherein I provide abutting flanges or projections 3, 4 at the ends of the ties which flanges or projections form a part of the ties in combination with projections 22 appurtenant to certain of the ties and which 75 prevent creeping of the rails, I provide a track structure wherein the ties mutually support one another against displacement and one wherein the rails are held from 80 creeping. By thus providing the abutting 85 projections on the ties, I obtain the important result that it becomes necessary to provide projections 22 on but few ties per rail length, it being in fact necessary in most instances to provide projections 22 appurtenant to but one tie per rail length. This 90 serves to simplify the structure and makes it possible to provide the anti-creeping arrangement at low cost.

The use in the combination of angle bars 95 3 and 4 at the ends of the ties after the manner illustrated is of especial utility since the vertical parts or plates of the angle bars serve to anchor the ties in the ballast against endwise movement while the abutting of the 100

angle bars at their ends serves to hold all the ties against sidewise movement. With this arrangement, therefore, the ties of the track structure are firmly held in position.

• What I claim as new and desire to secure by Letters Patent of the United States, is:—

1. In a track structure, the combination of a plurality of ties having abutting projections at their ends whereby the ties mutually support each other, a rail on the ties, and abutting projections on the rail and at least one of the ties to prevent creeping of the rail.

2. In a track structure, the combination of a plurality of ties, each tie having transversely-extending angle irons at its ends

which form a part of the tie structure, the angle irons of adjacent ties abutting each other, a rail on the ties, and abutting projections on the rail and at least one of the ties to prevent creeping of the rail.

3. In a track structure, the combination of a plurality of ties, each tie having transversely-extending plates at its ends which project beyond the confines of the tie and form a part of the tie structure, the plates of adjacent ties abutting each other whereby the ties serve to mutually support one another.

In witness whereof, I have hereunto set my hand this 15 day of September, 1927.

WILLIAM DALTON.
